Inventor

UNITED STATES PATENT OFFICE.

LACY VICK, OF VICKSBURG, KENTUCKY.

COMPOUND TOOL.

SPECIFICATION forming part of Letters Patent No. 723,764, dated March 24, 1903.

Application filed November 3, 1902. Serial No. 129,794. (No model.)

To all whom it may concern:

Be it known that I, LACY VICK, a citizen of the United States, residing at Vicksburg, in the county of Livingston and State of Kentucky, have invented certain new and useful Improvements in Compound Tools, of which the following is a specification.

My invention relates to improvements in compound tools; and the object of my invention is the provision of a tool the head of which can be quickly and easily adapted to form a hammer, hatchet, chisel, hand-ax, or other tool, the various implements each performing their function in a perfect manner and the tool as an entirety being capable of production at a very low price.

Another object of my invention is the provision of a tool which will perform the several functions each in an efficient manner and which will be durable and entirely practical.

With these objects in view my invention consists of a compound tool embodying novel features of construction and combination of parts, substantially as disclosed herein.

Figure 1 represents a perspective view of my compound tool, the head being fitted with two implements—a hammer and adz or cutting-tool. Fig. 2 represents a central vertical sectional view. Fig. 3 represents a view of a modified construction, and Fig. 4 represents a detail view of another modified construction.

In the drawings, A designates the head, which is formed with the vertical opening B, which receives the upper end of the handle C, and the head is further provided with the end square openings or sockets D, which receive the squared end E on the various implements F, and these implements are retained in place by means of the clamping-screws G, which pass through the head and bear upon the squared ends of said implements. The openings in the ends of the head pass through to the vertical opening B, and the ends of the implement bear upon the ends of the handle and in addition to securing the implements in place serve also to bind and hold the handle in the head, as well as to secure the implement.

In the modified form of my invention shown in Fig. 3 the head is provided with the screw-

threaded openings or sockets H, which align when the parts are in position with sockets or seats J in the handle, and the implements have each a threaded stem K, which engages the threaded socket of the head and enters the sockets K of the handle, and this construction serves to secure the implements in the head and at the same time secure the handle firmly in the head, as will be understood.

In the modified form of my invention shown in Fig. 4 I provide the head with end sockets L, which extend through to openings or sockets M in the handle, and the stems N on the implement pass through the openings of the head into the openings of the handle, and the binding-screws O engage the stems, and thus hold the implements in the head and secure the handle to the head, as is evident.

It will thus be seen that I provide a compound tool which will perform the functions of various implements in a perfect manner and which can be produced as cheaply as either of the implements singly and will thus commend itself as a practical and desirable article.

I claim—

1. The tool herein described, consisting of the handle having a socket on each side near its upper end, the head fitting on said handle and having a transverse socket in each end alining with the sockets in the handle, implements having reduced shanks fitting in the sockets of the head and handle, and means for engaging the shanks to secure the implement in the head and to secure the head firmly upon the handle.

2. The tool herein described, consisting of the handle, the head formed with the handle-receiving opening, and having transverse sockets in the ends passing through to the handle-receiving opening, the implements having shanks fitting in the said sockets and engaging each side of the handle to secure the handle in the head, and binding-screws for securing the shanks firmly in the head.

In testimony whereof I affix my signature in presence of two witnesses.

LACY VICK.

Witnesses:

MOODY HARDIN,
P. R. VICK.
